Attorney

UNITED STATES PATENT OFFICE.

SANTINO BADO, OF MOUNT VERNON, NEW YORK.

PIPE PROTECTOR.

Application filed July 28, 1921. Serial No. 488,057.

To all whom it may concern:

Be it known that I, SANTINO BADO, a subject of the King of Italy, residing at Mount Vernon, in the county of Westchester and State of New York, have invented certain new and useful Improvements in Pipe Protectors, of which the following is a specification.

This invention relates to new and useful improvements in protectors for metallic pipes or the like.

An important object of the invention is to provide improved means for preventing rusting of metallic water pipes.

Another object is to provide improved means for preventing freezing of water in metallic supply pipes.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a fragmentary view of a pipe having a rust-proof covering in accordance with the present invention,

Figure 2 is a transverse sectional view taken upon line II—II of Figure 1,

Figure 3 is a fragmentary view of a pipe having an anti-freezing cover constructed in accordance with the present invention, and

Figure 4 is a transverse sectional view taken upon line IV—IV of Figure 3.

Referring to Figures 1 and 2, the pipe sections 12 may be suitably protected from rusting when situated in damp places by covering the same with a layer of tar paper 15 and then wrapping a layer of tarred twine or Russian rope 16 tightly thereon to which is applied a thin film or coating 17 of tar so as to provide a smooth water-proof surface for the covering. When the pipes are thus covered, they are effectively prevented from rusting by the prevention of moisture coming in contact with the outer surface thereof and the life of the pipe is thus prolonged.

Referring to Figures 3 and 4, should any of the pipe sections 12 be employed where the same is exposed to the air and in such manner that the same is constantly filled with water, there is danger of freezing of the water within said pipe sections and this may result in bursting of the pipe. In order to prevent freezing of exposed pipe sections, the same may be coated with a layer 60 of paint such as white lead or red lead 18 after which a layer of heavy twine 19 may be wound thereon with the windings contiguous as is the case with the windings of the twine 16 in Figures 4 and 5, and then a 65 second or outer layer of paint 20 is provided about the twine layer 19. In covering a pipe section in this way, the same is found to be well insulated and freezing of the water within the pipe section effectively prevented. It is to be understood that the term "paint" is herein employed to mean a semi-solid or plastic substance such as white lead or red lead, or even putty.

It is believed that the construction, manner, of use and advantages of the present invention will be readily appreciated and understood from the foregoing description by those skilled in the art.

Minor changes may be made in the invention without departing from the spirit and scope thereof.

What is claimed as new is:

1. In combination with a metallic pipe, a layer of tar paper contacting the outer 85 surface of the same and completely covering said surface, a layer of tar rope wound about said tar paper with the windings contiguous, and a layer of tar applied to said twine layer providing a smooth outer surface.

2. In combination with a metallic pipe, a layer of fibrous material contacting the outer surface of the same completely covering said surface, a layer of tar rope wound about 95 said fibrous material with the windings contiguous and a layer of viscous substance applied to said twine layer providing a smooth outer surface.

In testimony whereof I affix my signature. 100

SANTINO BADO.
